AUTOMATIC CRIMPING MACHINE

Felix M. Anthony, 275 Fairmount Ave., Piedmont, Calif.
Filed Jan. 22, 1962, Ser. No. 167,707
9 Claims. (Cl. 72—110)

This invention relates to cable connector crimping machines, in general, and is particularly directed to a fully automatic power driven machine of this type.

Various devices are known for facilitating the attachment of cable connectors, lugs, and other appliances to electrical cables by a crimping action. The appliance is commonly arranged to be slipped coaxially over the stripped end of a cable. The crimping tool is then arranged to grip the cable and appliance and to urge a crimping roller against the periphery of the appliance with substantial force while the roller moves circumferentially therearound. The appliance is thus circumferentially crimped into the cable conductor to produce a highly efficient connection therebetween. Heretofore the crimping tools have usually effected the crimping action by hand operation through a ratchet actuation or the like. By virtue of the substantial roller pressure which must be generated and the number of roller passes around the appliance required in producing a crimp, the use of hand operated crimping tools for this purpose is variously disadvantageous from the standpoints of the operating time and fatigue factor involved.

It is therefore an object of the present invention to provide a power driven fully automatic crimping machine for securing connection appliances to electrical cable in which the depth of crimp is uniformly controlled, thus providing for equal distribution of load pressure at the cable connection to assure maximum mechanical efficiency and electrical conduction.

Another object of the present invention is the provision of a crimping machine of the class described in which one or more crimps of the same or different diameters may be simultaneously formed.

It is another object of the present invention to provide a power driven fully automatic crimping machine which will secure connection appliances to electrical cable more accurately and with greater speed than has heretofore been possible.

Another object of the invention is the provision of a crimping machine in which a cable appliance disposed thereon may be placed and then in response to actuation of a single start switch or the like automatically effect a crimp lock of uniform depth between the cable and appliance.

Still another object of the invention is to provide a crimping machine of the class described which is readily adjustable to crimp cables and connection appliances of varied sizes without requiring the changing of dies or supplemental parts to accommodate such various sizes.

Yet another object of the invention is the provision of a crimping machine of the class described which makes two crimps at the same time on different diameters.

It is a further object of the invention to provide a crimping machine which is pneumatically powered.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

FIGURE 1 is a plan view with portions broken away of a crimping machine according to the present invention.

2

FIGURE 2 is a sectional view taken at line 2—2 of FIGURE 1.

FIGURE 3 is a sectional view taken at line 3—3 of FIGURE 1.

5 FIGURE 4 is a sectional view taken at line 4—4 of FIGURE 3.

10 FIGURE 5 is a partial side elevation of the crimping machine illustrating particularly a calibrated gauge of the adjusting means for adapting the machine to use with different size cables and connection appliances.

15 FIGURE 6 is a schematic diagram of the automatically controlled pneumatic drive system of the crimping machine.

Considering now the invention in some detail and referring to the illustrated form thereof in the drawing, there is seen to be provided a crimping machine 11 for automatically producing a circumferential crimp locked joint between a connection appliance 12 and electrical cable 13. Basically the machine includes a cable receiving and 20 rotating bed 14 including drive and idler rolls 16, 17. Powered drive means, preferably a pneumatically actuated drive system 18 are coupled to the drive roll 16 to rotate same alternately in opposite rotational directions. Thus the cable 13 with connection appliance 12 concentrically disposed thereon may be placed upon the bed between the drive and idler rolls 16, 17. Upon actuation 25 of the drive system 18 the drive roll imparts its alternating rotary motion to the cable and appliance to rotate same alternately in one direction through at least 360° and then in the opposite direction through at least 360°.

30 In addition the crimping machine 11 includes a crimping roll 19 journaled upon feed means 21 for rotation about an axis parallel to the rotational axes of rolls 16, 17 and in spaced opposition to the region intermediate same. The crimping roll thus bears against the surface of the connection appliance 12 as disposed upon the cable 13 and supported on the drive and idler rolls. Moreover, the feed means 21 is arranged to gradually urge the crimping roll into closer and closer intimate contact with the connection appliance 12 as it is rotated. Such action of the feed means is facilitated by powered drive means, preferably a pneumatic feed drive system 22 coupled thereto. In addition, a pneumatic control system 23 couples the drive systems 18 and 22 to a compressed air source 24. The control system is arranged to effect energization of the rotary drive system 18 in a manner productive of the alternating rotation and simultaneously effect energization of the feed drive system 22, all in response to selective actuation by an operator. When the feed drive system 22 has urged the crimping roll 19 to a predetermined depth of penetration into the connection appliance 12 productive of a crimped joint, the control system automatically disconnects the drive systems 18, 22 from the air source 24 to thus terminate operation of the machine. The crimping machine 11 thus produces a circumferential crimped joint between the connection appliance 12 and cable 13 in a fully automatic manner in response to a single actuation by the operator.

60 Considering now the crimping machine 11 generally outlined hereinbefore in greater detail as to preferred structure, it is to be noted that the bed 14 is provided as a generally rectangular open topped housing 26 between the side walls of which the drive and idler rolls 16, 17 are journaled in parallel close longitudinally spaced relationship. The side walls of the housing are provided with suitable notches 27 in their regions medially of the rolls to provide exposed accessible roll surfaces for freely supporting the connection appliance and cable thereon. It is important to note that the drive and idler rolls 16, 17 are identical and that each includes transversely 65 spaced peripheral portions 28, 29 of different diameters.

More specifically the outer peripheral portion 28 of each roll is of somewhat greater diameter than the inner peripheral portion 29. The peripheral portions 28, 29 are spaced and interconnected by an integral central hub portion 31 of the roll having a lesser diameter than either of the peripheral portions. The surfaces of the peripheral portions are preferably knurled. It will thus be appreciated that the space between the inner peripheral portions 29 of the drive and idler rolls is greater and deeper than the space between the outer peripheral portions 28. The connection appliances 12 include correspondingly enlarged and reduced portions for respectively engaging the insulating sheath and stripped bare conductor of the cable 13. Thus the rolls facilitate the ready support of the connection appliance with its enlarged portion engaging the inner peripheral roll portions 29 and its reduced portion engaging the outer roll portions 28 as best shown in FIGURE 1.

The axle of the idler roll 17 is journalled for free rotation directly between the sides of housing 26 while the axle of drive roll 16 projects inwardly therefrom for coupling to the pneumatically actuated drive system 18. More specifically the drive system 18 is preferably contained within a longitudinally elongated housing 32 to the outer side wall of which the bed housing 26 is secured. The bed housing is so disposed relative to the drive housing 32 that the projecting end of the drive roll axle transversely overlies the top wall of the latter. The system 18 then preferably includes a double acting pneumatic cylinder 33 mounted longitudinally within the central region of the housing 32. The piston rods 34, 36 secured to the piston 37 within cylinder 33 project from its opposite ends and are secured to a longitudinally extending rack 38. The rack is slidably interposed between the cylinder 33 and top wall of housing 32 in parallel relation to the piston rods 34, 36. Brackets 39 extending radially from the piston rods into attachment with the rack are the preferred means of securance therebetween. As the piston reciprocates within the cylinder the rack is hence correspondingly moved within the housing 32 adjacent its top wall. The rack is disposed with its teeth facing the top wall of the housing so as to engage a gear 41 secured to the projecting end of the drive roll axle and having its periphery extending through a slot 44 in the top wall. Thus the reciprocating motion of the rack produces rotation of the gear and drive roll alternately in opposite directions.

Considering now the crimping roll 19 which bears against the connection appliance to be crimped during the alternating rotation thereof effected by the drive roll 16, it is to be noted that such crimping roll is formed with a pair of transversely spaced integral rims 46, 47. These rims are adapted to be positioned in alignment with longitudinal vertical planes medially through the peripheral portions 28, 29 respectively of the drive and idler rolls. The outer rim 46 is of greater diameter than the inner rim 47 so as to conform to the different spacings between the peripheral portions of the drive and idler rolls.

With reference to the crimping roll feed means 21, it is to be noted that same preferably includes a pivot bracket 48 upon which the drive roll is journalled. The bracket has a pair of parallel spaced side arms 49, 51 joined at one end by a cross member 52, the axle of the crimping roll being rotatably secured between the opposite ends of the arms. The bracket is pivotally connected at a point 53 adjacent the crimping roll, between upwardly and longitudinally projecting extensions 54 of the side walls of a generally rectangular open topped feed housing 55. The distal ends of the bracket arms relative to the crimping roll project from the pivot into overlying relation to the well 56 defined by the housing 55. The housing 55 is arranged to be vertically translatable relative to the bed housing 26 and in this regard it is to be noted that the extensions 54 lap the sides of the bed housing at the rearward end thereof. The ex-

tensions 54 are formed with ribs 57 which slidably engage vertical grooves 58 provided in the sides of the bed housing. With the feed housing so mounted relative to the bed housing it is to be noted that the crimping roll overlies the medial regions between the feed and idler rolls in the relationship hereinbefore described. Moreover, springs 59 are attached between the bracket side arms 49, 51 and the base of the feed housing on the opposite side of the pivot 53 from the crimping roll. The springs resiliently retain the bracket in a normal position wherein the crimping roll is spaced from the drive and idler rolls. Upon upward movement of the distal end of the bracket relative to the crimping roll the roll is pivoted downwardly towards the drive and idler rolls between upper and lower limits of the feed stroke which are fixed relative to the feed housing and determined in a manner subsequently described.

It is desirable that the limits of the feed stroke of the crimping roll be readily varied with respect to the drive and idler rolls such that different sizes of connection appliances and cables may be accommodated by the crimping machine. To this end means are provided to adjustably vertically translate the feed housing relative to the bed housing whereby the positions of the upper and lower limits of the feed stroke are likewise translated relative to the drive and idler rolls. Preferably the adjusting means includes a screw shaft 61 journalled in the bottom of the bed housing for rotation about a vertical axis. The shaft threadably engages a lug 62 secured to the front wall of the feed housing 55 so that as the shaft turns the feed housing is vertically translated. To facilitate turning of the shaft a shaft extension 63 may be releasably keyed to the free end of the shaft to extend upwardly above the feed housing. An adjusting wheel 64 may additionally be secured to the lower end of the shaft which projects below the bottom of the bed housing whereby rotation of the shaft may be alternatively effected. Moreover, in order that the positions of the feed stroke limits be easily set to properly accommodate the different size cables and connection appliances a size gauge is advantageously provided at the front of the bed and feed housings. More particularly, an indexing arrow 66 is scribed or otherwise imprinted on one housing, for example, the feed housing, adjacent the part line therebetween. A number of vertically spaced lines 67 calibrated in terms of cable size are in turn provided on the other housing, in this case the bed housing. Accordingly, the adjusting wheel 64 may be turned until the arrow is aligned with the particular line 67 that is calibrated with the desired cable size. The feed stroke limits of the crimping roll are at this time positioned relative to the drive and idler rolls to properly accommodate that size of cable and its corresponding connection appliance.

With the feed means 21 provided as just described the pneumatic drive system 22 for driving same preferably comprises a single acting pneumatic cylinder 68 vertically mounted within the well 56 defined by feed housing 55. The piston rod 69 of cylinder 68 extends vertically upward through the upper end of the cylinder into connection with the cross member 52 of the pivot bracket 48. Thus when the cylinder is energized and its piston is pneumatically urged upward the bracket is pivoted to urge the crimping roll gradually downward towards the drive and idle rolls. When the crimping roll reaches the lower limit of its stroke the cylinder is ported in a manner subsequently described such that the springs 59 acting on the bracket force the piston downward to the lower end of the cylinder. It will be appreciated that the piston as disposed at the lower end of the cylinder determines the upper limit of the feed stroke of the crimping roll.

Considering now the pneumatic control system 23 in detail, it preferably includes a 4-way valve 71 connected as depicted in FIGURE 6 to effect the alternating reciprocation of the piston of double acting cylinder 33. The ports at the opposite ends of cylinder 33 are re-

spectively connected to opposed ports 72, 73 of the valve 71. One of the other valve ports 74 is vented to atmosphere while the remaining port 76 is arranged to be selectively coupled to the compressed air supply 24. In addition the pneumatic actuating ports 77, 78 of valve 71 are respectively connected to trip valves 79, 81 disposed at the opposite ends of the housing 32 so as to be engageable with the rack support brackets 39 as the rack reciprocates between the opposite ends of the housing. One trip valve 79 is preferably fixedly secured to the housing while the other trip valve 81 is selectively longitudinally translatable relative thereto. To this end valve 81 is coupled to a lead screw translating mechanism 82 or equivalent means as best shown in FIGURE 1. It will be appreciated that as air is supplied from one port 72 of valve 71 to one port of the cylinder 33, the piston urges the rack towards one end of the housing 32. The leading bracket 39 then engages for example trip valve 79, which valve in turn actuates the 4-way valve 71 to reverse the flow conditions therethrough. The first port of the cylinder is now vented to atmosphere through valve port 74 while air is supplied from valve port 73 to the port at the other end of the cylinder. The piston hence urges the rack in the opposite direction towards the other end of the housing and the trip valve 81. The leading bracket 39 engages the trip valve 81 and same operates to reverse the flow conditions through the 4-way valve. Thus the 4-way valve and trip valves are effective in producing the alternating rack reciprocation and therefore the alternating rotation of the feed roll 16. Moreover, it will be appreciated that adjustment of the lead screw translating mechanism 82 to vary the longitudinal position of trip valve 81 correspondingly varies the stroke length of the rack and therefore the angle of rotation of the drive roll. This is important in that smaller size cable and connection appliances require a smaller rotational angle of the drive roll than do larger sizes.

The control system 23 further includes a 3-way valve 83. Ports 84, 86 of the valve 83 are respectively connected to the supply port 76 of the 4-way valve and the port of the pneumatic cylinder 68. The other ports 87, 88 of the 3-way valve are respectively vented to atmosphere and connected to compressed air supply 24. The actuating ports 89, 91, of the 3-way valve are respectively connected to trip valves 92, 93. Trip valve 92 is mounted within the feed housing 55 in overlying relation to the pneumatic cylinder 68 so as to be engageable with the upper end of the piston rod 69 when the pivot bracket 48 is provided upward by the piston within the cylinder. The trip valve 92 upon being engaged by the piston rod is effective in actuating the 3-way valve to disconnect the air supply 24 from the ports 84, 86. As a result both cylinders are deenergized to terminate operation of the machine. The trip valve 92 thus determines the lower limit of the feed stroke of the crimping roll. The trip valve 93 is similarly operable to actuate the 3-way valve to disconnect the air supply from the valve ports 84, 86 and thus terminate operation of the machine. The trip valve 93 hence functions as a cycle stop switch. The 3-way valve includes a start switch 94 which is operable upon actuation to shift the 3-way valve to a position connecting the air supply 24 to the valve ports 84, 86 and thereby commence operation of the machine. It will, of course, be understood that the device may be adapted to also operate hydraulically to perform the same work.

In the over-all operation of the machine the shaft extension 61 is first rotated until the arrow 66 is aligned with the line calibration 67 indicative of the cable and connection appliance size to be crimped. The lead screw translating mechanism 82 is adjusted to provide an appropriate rotational angle of the feed roll 16. The cable and connection appliance are inserted between the crimping roll and feed and idler rolls. The start switch 94

is actuated to commence operation of the machine. The feed roll is thus rotatably alternated to similarly rotate the cable and connection appliance in alternately opposite directions. Simultaneously the crimping roll 19 is urged into closer and closer contact with the appliance periphery to crimp the appliance to the cable. When an appropriate depth of crimp is attained, the trip valve 92 is engaged to in turn actuate the 3-way valve to terminate operation of the machine. If at any time during the operating cycle of the machine it is desired to cease operation the cycle stop trip valve 93 is actuated.

From the foregoing it will be clear that the crimping machine of the present invention which will insure the formation of a crimp of uniform depth completely around the associated portions of the cable and connecting appliance, thus eliminating the possibility of any defects in the attachment such as commonly prevalent with the use of hand operated crimping devices. At the same time the crimping operation may be performed in considerably less time than with the hand type. It will additionally be seen that since the machine of the present invention is capable of forming practically any desired number of crimps on different diameters simultaneously, it becomes unnecessary to change dies or other supplemental parts when cables of different sizes or with different connection appliances are being operated upon.

What is claimed is:

1. A cable crimping machine comprising a bed with spaced drive and idler rolls journaled thereon, a crimping roll disposed in overlying relation to said drive and idler rolls, feed means mounting said crimping roll for rotation about an axis parallel to the axes of said drive and idler rolls and for translation towards and away from said bed, a powered drive system coupled to said drive roll to upon energization rotate the drive roll alternately in opposite directions, a powered feed system coupled to said feed means to upon energization translate said crimping roll towards said drive and idler rolls, and a control system coupled to said powered drive and powered feed systems to selectively effect simultaneous actuation thereof.

2. A cable crimping machine according to claim 1, further defined by said drive and idler rolls each having a pair of transversely spaced peripheral portions of different diameters and said crimping roll having a pair of transversely spaced rims respectively aligned with vertical medial planes through the spaced peripheral portions of said drive and idler rolls, the diameter of said rim aligned with the larger diameter peripheral portions being less than that of the rim aligned with the smaller diameter peripheral portions.

3. A cable crimping machine comprising a bed with longitudinally spaced drive and idler rolls journaled thereon for rotation about transverse axes, a pivot bracket journaled for rotation about a transverse axis upwardly disposed relative to the axes of said drive and idler rolls with a first end of the bracket overlying said rolls and pivotal upward and downward relative thereto, a crimping roll journaled for rotation about a transverse axis at said first end of said bracket, a pneumatic rotary drive system coupled to said drive roll for rotating same alternately in opposite directions, a pneumatic feed system coupled to the second end of said bracket to urge same upwardly, and a pneumatic control system coupled to said pneumatic drive and feed systems to selectively effect simultaneous energization thereof.

4. A cable crimping machine according to claim 3, further defined by said bracket being pivotally mounted within a feed housing, said feed housing vertically translatable relative to said bed, and adjustable translating means coupled between said bed and feed housing for selectively translating the latter to varied vertical positions relative to the former.

5. A cable crimping machine comprising a longitudinally elongated drive housing, a bed secured to one side

of said housing, longitudinally spaced drive and idler rolls journaled on said bed for rotation about parallel transverse axes, said drive roll having an axle projecting from said bed and overlying the top of said housing, a gear secured to the end of said axle and extending through the top of said housing into its interior, a double acting pneumatic cylinder mounted within said housing with piston rods extending longitudinally from the opposite ends of the cylinder, a rack longitudinally disposed between said cylinder and the top of said housing, said rack engaging said gear and secured to said piston rods, a feed housing at one end of said bed, a pivot bracket pivotally mounted within said feed housing for rotation about a transverse axis and having a first end overlying said rolls pivotal upwardly and downwardly relative thereto, a crimping roll journaled for rotation about a transverse axis at said first end of said bracket, a single acting pneumatic cylinder mounted within said feed housing and having a piston rod extending upwardly into connection with the second end of said bracket, spring means normally urging the second end of said bracket downward, and a pneumatic control system for selectively supplying compressed air alternately to the opposite ends of said double acting cylinder while simultaneously supplying compressed air to the lower end of said single acting cylinder.

6. A cable crimping machine according to claim 5, further defined by said feed housing being vertically slideable relative to said bed, and screw means coupled between said feed housing and bed for selectively translating the former to varied vertical positions relative to the former.

7. A cable crimping machine according to claim 5, further defined by said drive and idler rolls each having a pair of transversely spaced peripheral portions of different diameters and said crimping roll having a pair of transversely spaced rims respectively aligned with vertical medial planes through the spaced peripheral portions of said drive and idler rolls, the diameter of said rim aligned with the larger diameter peripheral portions being less than that of the rim aligned with the smaller diameter peripheral portions.

5 8. A cable crimping machine according to claim 5, further defined by said pneumatic control system comprising a 4-way valve having first and second ports respectively connected to the opposite ends of said double acting pneumatic cylinder and a third port vented to atmosphere and a fourth port, first and second trip valves disposed within said drive housing at its opposite ends and engageable with said rack, said trip valves coupled to said 4-way valve and operable upon engagement by said rack to reverse the flow between the ports of said 10 4-way valve, a 3-way valve having first and second ports respectively connected to the lower end of said single acting cylinder and to the fourth port of said 4-way valve and having third and fourth ports respectively vented to atmosphere and connected to a compressed air source, said 3-way valve having start switch means operable upon actuation to establish flow in said 3-way valve between its fourth port and the first and second ports thereof, and a third trip valve mounted within said feed housing and engageable with said second end of said bracket upon upward movement thereof a predetermined distance, said 15 third trip valve coupled to said 3-way valve and operable upon engagement with said bracket to shift said 3-way valve to a position blocking flow between its fourth port and the first and second ports thereof.

20 9. A cable crimping machine according to claim 8, further defined by said first trip valve being selectively longitudinally translatable within said drive housing.
